SPORTS BOOT

Joseph P. Famolare, Jr., Florence, Italy, assignor to Famolare, Inc., New York, N.Y.

Filed Mar. 15, 1973, Ser. No. 341,681

Term of patent 14 years

Int. Cl. D2—04

U.S. Cl. D2—276

FIG. 1

FIG. 3

FIG. 1 is a front perspective view of a sports boot showing my new design;

FIG. 2 is a rear elevational view thereof; and

FIG. 3 is a side elevational view.

I claim:

The ornamental design for a sports boot, substantially as shown and described.
